US0D1075121S

(12) United States Design Patent (10) Patent No.: US D1,075,121 S
(45) Date of Patent: * May 13, 2025

(54) PROJECTOR LAMP

(71) Applicant: Xiaguang Liu, Dawu Township (CN)

(72) Inventor: Xiaguang Liu, Dawu Township (CN)

() Term: 15 Years

(21) Appl. No.: 29/936,452

(22) Filed: Apr. 9, 2024

(30) Foreign Application Priority Data

Feb. 29, 2024 (EM) 015052281-0001

(51) LOC (15) Cl. 26-05

(52) U.S. Cl.

USPC D26/99; D21/637

(58) Field of Classification Search

USPC D11/131, 157, 158, 160; D16/221, 222; D21/483, 576, 594, 621, 627, 630, 631, D21/634, 636, 637; D26/24, 73, 93, 94, D26/98, 99, 104, 106, 108, 110-112, 113, D26/118, 125, 126

CPC F21S 6/00; F21S 6/002; F21S 6/003; F21S 10/007; F21S 10/02; F21S 10/06; F21S 10/063; F21W 2121/008

CLAIM

The ornamental design for a projector lamp, as shown and described.

DESCRIPTION

FIG. 1 is a perspective view of my new design, showing a projector lamp;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The line shading in FIGS. 1-8 represents contour and not surface ornamentation.

The broken lines shown in the figures illustrate portions of the article that form no part of the claimed design.

1 Claim, 8 Drawing Sheets
